APPARATUS FOR MANUFACTURE OF
TYPE FONTS

De Forest F. Neely, Kansas City, Mo.

Application November 8, 1948, Serial No. 58,873

3 Claims. (Cl. 101—401.5)

1

This invention relates to machines for producing an article of manufacture in the nature of a type font or shuttle forming a part of a typewriting machine commonly referred to in the field as the "Variyper," the primary object being to facilitate the manufacture thereof from the standpoint of pressure, simplicity and cost.

The most important object of the present invention is to provide a machine for forming type fonts having a pair of relatively shiftable die members for receiving the font blank therebetween and exerting extreme pressure thereon, one of the die members having types formed in intaglio for creating raised type upon the blank through flow of the metal from which the blank is made into the types of the die.

Another important object of this invention is to provide a machine for producing type fonts capable of creating the raised type thereon, irrespective of the fact that the font blank is longitudinally arcuate through the provision of a split die having means of relative separation between the parts thereof after the font has been formed.

A further object of the present invention is to provide a machine of the aforementioned character, wherein one of the die members has a plurality of longitudinal ribs formed thereon for automatically forming rib and groove structure on the innermost face of the font while the type face thereof is being formed.

In the drawing,

Fig. 1 is a side elevational view of apparatus for manufacturing type fonts and the like made in accordance with the present invention, parts being broken away and in section to reveal details of construction.

Fig. 2 is a transverse, cross sectional view taken on line II—II of Fig. 1.

Fig. 3 is a substantially central, vertical, cross sectional view taken on line III—III of Fig. 1.

Fig. 4 is a fragmentary, detailed, top plan view of the lowermost die of the machine.

Fig. 5 is a side elevational view of the segment of a type font manufactured by the machine forming the subject matter hereof; and

Fig. 6 is a detailed, cross sectional view taken on line VI—VI of Fig. 5.

In the drawing, a base member broadly designated by the numeral 10 is provided with a flapped, lowermost surface, to the end that the same is adapted for support upon any stand, table or the like. Base 10 has substantially the same plan contour as reciprocable member 12 shown in Fig. 2 of the drawing. Such contour includes a pair of opposed ears 14 and 16, each

2

of which has extending upwardly therefrom and fixed rigidly thereto an elongated post 18.

These vertical posts 18 have their longitudinal axes substantially parallel and the ears 20 and 22 of the reciprocable member 12 are provided with openings 24 and 26, respectively, for receiving the posts 18. Thus, posts 18 serve as guide members for the member 12 that slides vertically thereon when the machine is placed in operation.

10 A tapped opening 28 is formed in the member 12 intermediate the ends thereof for receiving reduced, externally-threaded end 30 of an upwardly-extending rod 32. It is contemplated that the rod 32 have connection with structure 15 for imparting reciprocable movement to the member 12 upon the posts 18. Since, as will hereinafter be made known, tremendous pressure is necessary, any suitable hydraulic means would constitute the preferred form of the actuating medium for the rod 32. Since such operating mechanism forms no part of this invention, the same has not been shown or detailed.

20 A die member 34 is mounted upon the lowermost face of the member 12 and welded or otherwise secured thereto intermediate the ends of member 12 in opposed relationship to rod 32. The outermost free face 36 of the die 34 is arcuate for purposes hereafter to be made clear, and a pair of spaced, substantially parallel, longitudinal ribs 38 are formed on arcuate face 36.

25 Somewhat narrower rib 40 is, also, formed on the arcuate face 36 that extends longitudinally through the length of die 34 and is disposed midway between the ribs 38. The cross sectional contours of ribs 38 and the rib 40 are polygonal, as illustrated in Fig. 3 of the drawing.

30 In addition to the laterally-extending, opposed ears 14 and 16, the base member 10 is provided with an upstanding body portion 42 disposed between the upstanding posts 18. Body 42 is substantially U-shaped to present a pair of polygonal blocks 48 and 50 occupy a portion of the space between the legs 44 and 46.

35 These blocks 48 and 50 are preferably formed integral with the base section 10, and the uppermost faces thereof terminate a short distance below the uppermost free ends of the legs 44 and 46. As illustrated in Fig. 3 of the drawing, these blocks 48 and 50 are appreciably narrower than the proximal legs 44 or 46, against which the same are disposed.

40 The space between the blocks 48 and 50 is normally occupied by an elongated piston 52 that passes freely through a bore 54 formed vertically and centrally throughout the base section

10. Piston 52 has its lowermost end disposed within a cylinder 56 forming a part of hydraulic structure for imparting reciprocable movement to the piston 52. The instrumentalities for actuating piston 52 in this manner may be of conventional character and of the kind well known by those skilled in the art; and, therefore, they have not been shown. A reduced head 58 is formed on the uppermost end of the piston 52.

The body 42 carries a pair of opposed plates 60 and 62 that span the distance between the legs 44 and 46 and are secured to the body 42 by means of a plurality of screws or the like 64. Each plate 60 and 62 is, in turn, supplied with a pair of spaced, upturned ears 66 next adjacent each leg 44 and 46, respectively, said ears 66 having elongated, vertical slots 68 formed therein.

A die member broadly designated by the numeral 70 constitutes a pair of substantially identical sections 72 and 74. These sections 72 and 74, when in the operative position illustrated in Figs. 1, 3 and 4, form together an arcuate, uppermost surface and a flat lowermost face that rests directly upon the head 58 of piston 52 and upon the uppermost faces of the blocks 48 and 50.

Each section 72 and 74 is provided with a pair of opposed pintles 76 next adjacent the lowermost and outermost corner thereof that pass through the corresponding elongated slot 68 for free, sliding and rotative movement therein. The proximal, innermost ends of the two sections 72 and 74 are spaced apart when the die member 70 is in the full line position of Fig. 1, except for the provision of an overlapping, outturned flange 78 that is provided on the section 74 for bridging the distance between the sections 72 and 74.

Three rows of type 80 are formed in intaglio upon the uppermost concave face of the die member 70, these rows of type 80 being substantially parallel and extending longitudinally with respect to the die member 70. The overlapping flange portion 78 of the section 74 is, also, provided with identifying serial numbers in intaglio designated by the numeral 82.

Each of the legs 44 and 46 has its innermost and uppermost edge rounded as at 84. A continuous, upturned flange 86 is formed on the two sections 72 and 74 of die members 70 in the manner illustrated in Figs. 1, 3 and 4 of the drawing.

In operation, a longitudinally, arcuate blank of metallic material and designated by the numeral 88 is placed upon the uppermost concave surface of the die member 70 immediately below the die member 34. The peripheral dimension of this blank 88 is predetermined to fit snugly within the confines of the upturned, continuous flange 86 when the blank 88 is forced thereto.

It is understood that, when the machine is initially placed in operation, with the blank 88 positioned as just described, the sections 72 and 74 of die 70 will be disposed in the full line position of Fig. 1 of the drawing, resting upon the blocks 48 and 50. The piston 52 will be restricted sufficiently to permit such positioning of the die member 70.

The reciprocable member 12 is thereupon caused to be moved downwardly, where the convex face 36 thereof contacts and rests upon the concave face of the blank 88. Relatively great pressure is then exerted upon the member 12 and, consequently, upon the die 34 to forcibly press the blank 88 against the type 80.

When such action takes place, the metal forming the blank 88 will readily flow into the type 80 of die member 70 and form on the outermost

concave face of the blank 88 three rows of raised type 90 forming a part of the completed shuttle segment broadly designated by the numeral 92 and illustrated in Figs. 5 and 6 of the drawing.

5 By the same token, the extreme pressure that is being brought to bear between the dies 34 and 70 will form on that face of the blank 88 opposite to the type 90 a pair of longitudinal grooves 94 and 86.

10 These grooves, obviously, correspond to the ribs 38 and the face 36 of die member 34. Similarly, the relatively narrow rib 40 of die member 34 will create a longitudinal groove 98 upon the normally innermost face of the type font section 92.

15 It is to be understood and noted in Fig. 5, also, that a transverse rib 100 is formed on the normally innermost face of the font section 92 intermediate the ends thereof. The length of this 20 rib 100 is substantially the same as the distance between the two ribs 38 of the die member 34 and traverses the rib 40. Formation of the rib 100 is accomplished by a corresponding groove 102 formed in the face 36 between ribs 38 and 25 shown in Fig. 1 of the drawing.

As explained in my co-pending application filed on even date herewith and entitled "Type Font for Typewriting Machines," now Patent No. 2,523,538, the longitudinal groove 98 is formed in 30 the font section 92 for receiving a second section of the shuttle in the form of an arcuate web-like member for reinforcing the section 92 and serving as a means for mounting the entire shuttle within a typewriting machine.

35 This web member (not shown) is provided with a small notch intermediate the ends thereof that receives the rib 100 of section 92 to positively position the two sections of the font relative to each other and assure correct disposition of the 40 letters 90 with respect to the mounting means for the shuttle.

As noted in Figs. 5 and 6 of the drawing, the outermost faces of all of the letters 90 are flat. Consequently, once the blank 88 is pressed in 45 place in the manner above described, the finished font section could not be removed from the die 70 if it were not for the sectional characteristic thereof. Thus, in the removing operation, the member 12 is first shifted upwardly to the 50 position illustrated in Figs. 1 and 3 of the drawing.

Piston 52 is thereupon moved upwardly to strike the lowermost faces of the sections 72 and 74, causing the same to move upwardly with respect to the uppermost faces of blocks 48 and 50 55 and, at the same time, to tip outwardly upon the rounded corners 84 of legs 44 and 46. This action of the piston 52 upon the die member 70 will break loose the completed section 92 from the die member 70, whereupon the machine can be placed in use for producing another font 92.

60 It is apparent from the foregoing that type fonts of the character illustrated in Figs. 5 and 6 of the drawing can be made quickly and easily through use of the machine just described. The 65 necessity of producing the section 92 into a plurality of smaller segments, as has heretofore been the practice, is unnecessary.

A single strip of material may be used to produce the blank 88; and, when the type 90 is produced thereon, there is an assurance that each of the three rows thereof is correctly positioned with respect to the remaining rows and that each letter of each row is in perfect alignment, both with respect to the longitudinal axis and the transverse axis of the section 92.

The cost of production is lowered appreciably and, when the font itself is placed in use, the operator can be assured that the letters appearing upon the typewritten page will all be in correct alignment and evenly spaced in the proper manner.

By provision of a relatively sturdy structure, there is, also, an assurance that each and every impression made upon the blank 88, on both faces thereof, will be the same on every blank used. Also, the blank 88 cannot be displaced because of the provision of flange 86.

Finally, through elimination of a large number of steps in the process of manufacture, it is possible to produce type shuttles of the character illustrated in a minimum amount of time and with a tremendous saving in labor.

It is manifest that the particular machine forming the subject matter of this invention is subject to many changes and modifications that are well within the spirit of this invention, as defined by the scope of the appended claims.

Having thus described the invention, what is claimed as new and desired to be secured by Letters Patent is:

1. A machine for forming raised type on one face of an arcuate metallic blank, said machine comprising a pair of opposed die members mounted for relative shifting movement toward and away from each other, said die members having complementary arcuate faces, one of said die members having type formed in intaglio on the arcuate face thereof, for producing said raised type when the blank is pressed between the die members, said one die member being segmental; and means for swingably mounting the segments of the one die member for movement to and from an operative position forming said arcuate face thereof.

2. A machine for forming raised type on one face of an arcuate metallic blank, said machine comprising a pair of opposed die members mount-

ed for relative shifting movement toward and away from each other, said die members having complementary arcuate faces, one of said die members having type formed in intaglio on the arcuate face thereof, for producing said raised type when the blank is pressed between the die members, said one die member including a pair of pivotally mounted segments, and means for swinging said segments on their pivotal axes to break the blank loose from the one die member after said raised type has been formed on the blank.

3. A machine for forming raised type on one face of an arcuate metallic blank, said machine comprising a pair of opposed die members mounted for relative shifting movement toward and away from each other, said die members having complementary arcuate faces, one of said die members having type formed in intaglio on the arcuate face thereof, for producing said raised type when the blank is pressed between the die members, said one die member including a pair of pivotally-mounted segments, and means for swinging said segments on their pivotal axes to break the blank loose from the one die member after said raised type has been formed on the blank, said means including a ram normally disposed in underlying relationship to the segments and between the said pivotal axes.
